UNITED STATES PATENT OFFICE

KARL S. HOWARD, OF ST. LOUIS, MISSOURI, ASSIGNOR TO GENERAL STEEL CASTINGS CORPORATION, OF GRANITE CITY, ILLINOIS, A CORPORATION OF DELAWARE

LOCOMOTIVE STRUCTURE

Application filed April 27, 1931. Serial No. 533,325.

My invention relates to railway rolling stock and consists in a novel arrangement and construction of the throttle valve, steam piping, and cylinder saddle in a locomotive.

It has been customary in locomotive construction to locate the throttle valve either in the steam dome or in the upper part of the smoke box. In the former case, saturated steam is conducted from the valve in the dome to the T-head or super-heater header, as the case may be, through a dry steam pipe and then downwardly through the smoke box through live steam pipes leading to the valve chambers for the main steam cylinders. In the latter case, the saturated steam is led from the super-heater header through the throttle valve and then downwardly through the smoke box as in the former case. In either case, the live steam pipes leading from the super-heater header extend downwardly from the upper part of the smoke box on each side of the smoke box. The live steam pipes either lead through openings in the smoke box wall to the valve chambers on opposite sides of the cylinder saddle, or make connections with steam pipes in the saddle itself.

The main object of my invention is to locate the throttle valve, either single or multiple, as the case may be, in the main steam pipe or passage leading to the valve chambers and in the lower portion of the smoke box, or in the boiler support, so that the valve or valves and valve mechanism will be readily accessible from the outside.

Another object of my invention is to simplify the construction by forming the valve housing integral with the main steam pipe or the cylinder saddle and thus eliminate the joints which are necessary in a built-up structure.

Another object of my present invention is to eliminate one of the steam pipes from the smoke box, thus increasing the space available for other appliances and decreasing the

expense and labor incidental to installing the steam connections within the smoke box.

Another object of my invention is to eliminate the openings in the smoke box wall where the live steam pipes pass out to the valve chambers.

Another object is to provide a more permanent and secure mounting for the throttle valve than has been provided in previous designs of locomotives.

Another object is to form the live steam pipes integral with and extending across the saddle and forming a brace between the valve chambers.

I attain these objects and others which will appear from the following description by the structure illustrated in the accompanying drawings in which—

Figure 1 is a top view of a locomotive cylinder and a portion of the main frame embodying one form of my invention.

Figure 2 is a side elevation of the same showing the smoke box and an adjacent portion of the boiler in dot and dash lines.

Figure 3 is a front view of the same.

Figure 4 is a vertical longitudinal section taken on line 4—4 of Figure 1.

Figure 5 is a top view, sectional in part, taken on line 5—5 of Figure 7 and showing a modification of my invention.

Figure 6 is a side view of the same showing the throttle valve housing and a portion of the live steam pipe integral therewith.

Figure 7 is a front view of the same.

Figure 8 is a vertical longitudinal section taken on line 8—8 of Figure 5.

Figure 9 is a detail vertical transverse section taken on line 9—9 of Figure 2.

Figure 10 is a side view of a modified form of the structure shown in Figure 7.

Figure 11 is a substantially horizontal transverse section taken on the line 11—11 of Figure 10.

Figure 12 is a horizontal transverse section taken on the line 12—12 of Figure 13.

Figure 13 is a side view of a modified form of the structure shown in Figure 2.

In Figures 1 to 4, inclusive, and 9, illustrating one form of my invention, I indicate a portion of a locomotive underframe including side frame members 1, a front deck 2, and various transverse members as integral with a cylinder saddle structure including main steam cylinders 3, steam 10 trol chambers 4, and a smoke box support 5 including substantially upright side walls and an arcuate top plate 9. The frame may be, however, of a built-up construction and the cylinder saddle may be formed separately and secured to the frame by suitable means, without departing from the spirit of this invention.

Pairs of exhaust pipes 6 lead from the valve chambers 4 and merge in the passage 7 20 which extends upwardly into the smoke box 8 in the usual manner. The merged portion 7 of the exhaust pipe is shown integral with the arcuate top plate 9 of the cylinder saddle, although this feature is not essential to my 25 invention.

The cylinder saddle also includes live steam pipes 10 and 11 which extend downwardly and outwardly to the valve chambers 4 from an upright passage 12 on the right 30 side of the saddle. This passage 12 is preferably integral with the arcuate top plate 9 which surrounds the smoke box saddle, and a collar 14 also surrounds the passages 7 and 12 at their tops. Passage 12 merges with the 35 adjacent wall of the saddle, as indicated in Figure 9. Live steam pipe 11 extends behind upright exhaust steam passage 7 and the walls of these two members merge, as shown in Figure 4, thereby effecting a central 40 support for the transverse pipe 11. Live steam pipes 10 and 11 and exhaust pipes 6 are preferably integral with the smoke box saddle, valve chambers, and main steam cylinders.

A throttle valve housing or body 13 is formed integrally with the portion of live steam passage 12 which merges with the wall of the saddle and an outward opening is provided for inserting the valve mechanism 50 18 and to permit access thereto and operation thereof from the outside. A partition 12a extends across passage 12 adjacent valve body 13 and has a central perforation provided with a renewable annular valve seat 55 13a. A single pipe 15 conducts steam from the superheater header 15a downwardly through the smoke box, and this pipe connects with the upper end of passage 12. Pipes 10 and 11, constituting arms on the 60 lower end of the passage 12, conduct the live steam from the throttle valve to each valve chamber.

In the modification shown in Figures 5 to 8, the throttle valve housing 16 is formed 65 integrally with the live steam pipe 17 ex-

tending downwardly through the smoke box from the super-heater header or T-head (not shown). This pipe 17 connects with the substantially upright passage 28 which is divided at its lower end into arms 19 and 20 leading outwardly to the valve chambers 21. Exhaust steam passages 24 extend from the valve chambers through the saddle structure and merge in an upright passage 23 projecting into the smoke box. Arm 20 of the forked live steam member extends behind passage 23, and the walls of the two pipes merge, as shown in Figure 8, effecting a central support for the transverse arm 20.

Live steam pipe sections 17 and 28 are 70 curved to conform in a general way with the contour of the smoke box wall 25 and provide the maximum space for various devices within the smoke box. An opening is provided in the wall 25 adjacent valve housing 85 16 to permit access to the valve interior from the outside and also to permit operation of the valve. Partition 16a, extending across pipe 16, has a central opening and a renewable valve seat 22a.

The upright passages 28 and 23 are shown 90 as merged with the arcuate top web 26 of the saddle. These passages might, however, extend through holes in the web, or a portion of the web may form a collar similar to that shown at 14 in Figure 1 for further bracing the members.

The form shown in Figures 10 and 11 corresponds with that shown in Figures 5, 6, 7, and 8 except that valve housing 29 in live steam pipe 30 is enlarged to provide for a pair of throttle valves. A partition 31 extending across pipe 30 has a pair of openings 32 mounting renewable valve seats 33. Pipe 30 connects with a passage 34 leading upwardly into the smoke box from the valve chambers 35 as in Figures 5, 6, 7, and 8.

In Figures 12 and 13, corresponding with the form shown in Figures 1 to 4 and 9, a multiple valve housing 36 is formed in the enlarged portion of live steam pipe 37 which merges with the wall of saddle 38. Outward openings 41 are provided in the wall of the saddle for insertion of the valve mechanisms and renewable valve seats 39 are mounted in the partition 40.

I prefer to form the exhaust pipes, live steam pipes, smoke box saddle, valve chambers, and main steam cylinders in an integral structure with the locomotive underframe in all forms of my invention herein illustrated and described, but it would be within the spirit of the invention to form some of these elements separately and secure them to adjacent structure by means of bolts, rivets, or welding. The structure illustrated may also be modified as to various other details without departing from the spirit of the invention and I contemplate the exclusive use 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

of all such modifications as come within the scope of my claims.

I claim—

1. In a locomotive, an integral structure comprising a smoke box support, steam control chambers, and a live steam pipe, said live steam pipe comprising transverse portions extending between said chambers and an upright portion extending through the top of said support. 70
2. In a locomotive, a cylinder saddle, steam control chambers adjacent thereto, a smoke box mounted on said saddle, and a live steam pipe having transverse portions extending between said chambers and through said saddle and merging in a substantially upright portion extending into said smoke box; said saddle, chambers, and live steam pipe forming an integral structure. 75
3. A locomotive live steam pipe and a throttle valve housing integral therewith, said housing being arranged for a plurality of valves. 80
4. In a locomotive, the combination of an integral structure including a live steam pipe and throttle valve housing, and a renewable valve seat in said structure. 85
5. In a locomotive, the combination of an integral structure including a live steam pipe and an integral housing arranged for a plurality of throttle valves, and a plurality of renewable valve seats in said structure. 90
6. A locomotive cylinder saddle integral structure including a throttle valve housing arranged for a plurality of valves. 95
7. A locomotive cylinder saddle integral structure including a throttle valve housing, and a renewable valve seat in said structure. 100
8. A locomotive cylinder saddle integral structure including a throttle valve housing arranged for a plurality of valves, and a plurality of renewable valve seats in said structure. 105
9. A locomotive cylinder saddle structure having a throttle valve housing located therein and arranged for a plurality of valves. 110
10. In a locomotive, a cylinder saddle structure, a throttle valve housing located therein, and a renewable valve seat in said housing. 115
11. In a locomotive, an integral structure including a smoke box saddle, a live steam pipe extending through said saddle, a throttle valve housing within said steam pipe, and a renewable valve seat in said housing. 120
12. In a locomotive, an integral structure including a smoke box saddle, a live steam pipe extending through said saddle, and a throttle valve housing within said steam pipe, said housing being arranged for a plurality of valves. 125
13. In a locomotive, a smoke box, a steam supply member leading into the top of said smoke box, a saddle supporting said smoke box, a throttle valve located in said saddle, and a live steam pipe for conducting steam from said member to said throttle valve. 130
14. In a locomotive, a smoke box, a steam supply member extending into the upper part of said smoke box, a throttle valve located in the lower part of said smoke box, and a pipe for conducting live steam from the end of said member within said smoke box to said throttle valve. 135
15. In a locomotive, a cylinder saddle, steam valve chambers located adjacent said saddle, a smoke box mounted on said saddle, and live steam pipes extending from said chambers inwardly through said saddle and then merging in a single pipe extending upwardly through said saddle and into said smoke box. 140
16. In a locomotive, a saddle, a smoke box thereon, walls surrounding said box and saddle, means for conducting live steam through said smoke box comprising a single pipe leading through said smoke box substantially from top to bottom, and a throttle valve mounted within said pipe near its bottom end and located within said walls. 145
17. In a locomotive, a smoke box, means for conducting live steam through said smoke box comprising a single pipe leading through said smoke box substantially from top to bottom, and a plurality of throttle valves mounted within said pipe near its bottom end. 150
18. In a locomotive, a smoke box, means for conducting live steam through said smoke box comprising a single pipe leading substantially across said smoke box from top to bottom, and a throttle valve mounted within said pipe, said valve projecting through an opening in the wall of said smoke box. 155
19. In a locomotive, a cylinder saddle, valve chambers on each side of said saddle, live steam passages extending from said chambers inwardly through said saddle and merging in a single passage extending up through the top of said saddle, and a throttle valve mounted in the merged portion of said passages and projecting through an opening in the side of said saddle. 160
20. In a locomotive, a smoke box saddle, an exhaust steam pipe extending upwardly through the top thereof, and a live steam pipe in said saddle having an upwardly extending portion and transverse portions extending from each side of said saddle and merging in said upwardly extending portion, one of said transverse portions being supported by said exhaust pipe. 165
21. In a locomotive cylinder saddle structure, a plurality of substantially upright walls adapted to mount a smoke box, exhaust steam pipes extending between opposite walls of said structure and merging in an upwardly disposed passage extending beyond the top of said structure, and live steam pipes extending transversely of said structure and 170

merging in an upright portion spaced from said first mentioned passage, the wall of one of said transversely extending live steam pipes merging with the wall of said upright passage.

5 22. In a locomotive cylinder saddle structure, spaced valve chambers, exhaust steam pipes extending between said chambers and merging in an upright passage extending through the top of said structure, and a live steam pipe extending between said chambers and having an inlet connection intermediate its ends.

10 In testimony whereof I hereunto affix my signature this 21st day of April, 1931.
